UNITED STATES PATENT OFFICE.

GEORGE W. WHITTINGTON, OF INDIANAPOLIS, INDIANA.

MACHINE FOR WEAVING DIAMOND-MESH FENCING.

SPECIFICATION forming part of Letters Patent No. 768,102, dated August 23, 1904.

Application filed October 25, 1902. Renewed July 16, 1904. Serial No. 216,777. (No model.)

To all whom it may concern:

Be it known that I, GEORGE W. WHITTINGTON, a citizen of the United States, residing at Indianapolis, in the county of Marion and State of Indiana, have invented certain new and useful Improvements in Machines for Weaving Diamond-Mesh Fencing, of which the following is a specification.

This invention relates to improvements in machines for weaving fences having horizontal wires which are connected by intermediate wires woven to form a diamond-shape mesh between the said horizontal wires.

I accomplish the objects of the invention by the mechanism illustrated in the accompanying drawings, in which—

Figure 1 is a plan view of my invention; Fig. 2, a vertical section, central longitudinal, of Fig. 1; Fig. 3, a right side elevation of the main machine; Fig. 4, an elevation of the opposite or left side of the main body of the machine; Fig. 5, a rear elevation of the cross-bar which supports the wire-twisters, the twisters and retaining-caps being in place 25 on said bars and portions being in vertical section; Fig. 6, a like view of same cross-bar and twisters, showing in addition the mechanism for shifting the reciprocating portions of the twisting device; Fig. 7, a horizontal 30 section on the dotted line 77 of Fig. 6; Fig. 8, a transverse section of the said cross-bar and twisters on the line 88 of Fig. 6; Fig. 9, a side view and partial vertical section of detached parts which taken together form the 35 twister-shafts of the machine; Fig. 10, a view in side elevation of the parts of Fig. 9 assembled to form a twister-shaft; Fig. 11, an end view of Fig. 10 looking in the direction of the arrow; Fig. 12, a section on the line 12 40 12 of Fig. 9 looking in the direction of the arrow; Fig. 13, a detail in end view of the middle series of wire-carriers; Fig. 14, an end view of the outer series of wire-carriers; Fig. 15, a detail, on a larger scale, of the carriers 45 shown in Fig. 13, but showing the plate which supports the carriers and acts as a guard to keep the wires in the carriers in dotted lines. Fig. 16 is a detail in vertical section of Fig. 15 on the dotted line 1616 of said fig-

ure, and Fig. 17 is a view in side elevation of 50 the product of the machine.

Like characters of reference indicate like parts throughout the several views of the drawings.

The wires 1, from which the horizontal 55 strands of the fence are formed, are wound on spools 2 (see Figs. 1 and 2) of any usual and well-known construction. These spools are supported on suitable standards 3.

It will be noted on examination of Fig. 17 60 that the horizontal strands are closest together at the lower part of the fence, that the middle strands are farther apart than the lower strands, and that the strands of the upper third of the fence are farthest apart of all. The 65 drawings represent a fence having fourteen horizontal strands and diagonal wires connecting said horizontal strands, making a diamond-shaped pattern, and the machine illustrated is for the manufacture of such a fence. 70

A represents the loom or body of the machine where the weaving is done. Between said body and the spools 2 are the horizontally-mounted spools 4, which furnish the wires 5 for the cross-strands of the fence. 75 The spools 4 number one less than the number of horizontal strands. They are placed in two horizontal rows between the machine A and the standards 3, with their axes converging toward the said machine, as shown 80 in Fig. 1. In the operation of twisting the diagonal wires with the horizontal ones all of the twists in a given line transversely of the fence are made simultaneously. In said lines it will be noted that each alternate horizontal 85 wire has no diagonal wire twisted with it, and in a row having twists with the outside horizontal wires there will be seven twists, requiring seven cross-wires. These will be supplied from seven spools in the first row or row 90 of spools nearest to the machine. The outer row of spools will be six in number and will supply the cross-wires for the transverse row of twists in the fence, having but six twists in it. The means by which the cross-wires 95 are carried at proper intervals from one horizontal wire to another and by which the several wires to be woven into the fence are kept

from entanglement before reaching the wire-twisters form the essence of this invention. The reeling up of the finished product and the means for insuring a uniform progress of the wires through the twisters being the same as shown and described in a former application for patent made by me and filed at the Patent Office on the 25th day of July, 1902, Serial No. 117,028, will not be described.

10 6 represents a shaft mounted in suitable boxes on the frame A. It has the pulley 7, to which power is applied through belt 8.

9 is a shaft parallel with shaft 6 and having the spur gear-wheel 10, (see Fig. 3,) the cogs 15 of which engage those of the pinion 11 on the shaft 6. The outer side of the wheel 10 has the bevel-cogs 12, which extend less than half-way around the wheel on the side of the latter. These teeth engage the teeth of a bevel-

20 pinion 14 on the upper end of a shaft 15. A rotation of shaft 15 is obtained during less than half of each revolution of the wheel 10. Accidental rotation of shaft 15 is prevented by the flat-sided wing extension 16 from the 25 inner side of wheel 14 by the contact of the latter with the flat-sided track 17, projecting in the path of wing 16. This track ends opposite the beginnings of the teeth 12. The shaft 15 has the bevel-wheel 18, which en-

30 gages a like wheel 19 on the short horizontal shaft 20. The latter has a sprocket-wheel from which the link belt 21 (see Figs. 6 and 7) is driven. The belt passes across the machine to the sprocket-wheel 22 on the opposite side, and its function is to rotate the short shafts 23, having the cog-wheels 24, which 35 engage the cog-wheels 25 on the twister-shafts above said shafts 23.

40 Mounted on shaft 9 at the other side of the frame A is the wheel 76, having the side teeth 12^a, which, like the teeth 12 on the wheel 10, extend less than half-way around said wheel. The wheels 76 and 10 are set so their teeth 12^a and 12 will be on diametrically opposite 45 sides. A vertical shaft 15^a has the bevel-pin- 110 on ion 14^a. The latter engages the teeth 12^a. It also has the wing-plate 16^a to keep the wheel 14^a from revolving when the latter is not in engagement with the teeth 12^a. The shaft 15^a

50 has the bevel-wheel 18^a, which engages the wheel 19^a on the shaft carrying sprocket-wheel 22. By the above-described mechanism the link belt 21 is driven in alternate opposite directions during each revolution of the shaft 55 9, with intervals of rest between each change in the direction of said belt movement. The twister-shafts hereinafter to be described are correspondingly rotated to the right and then to the left, and so on, with intermediate pauses.

60 It is essential that all of the twister-shafts rotate equally and simultaneously; but as they are not uniform distances apart, but are grouped in three divisions, corresponding with the arrangement as to distances from each 65 other of the horizontal fence-wires, I connect

up the twister-shafts, through their associated shafts 23, as follows: The first five wheels 24 being those which operate the twisters for the bottom and closest wires of the fence engage with one another, as shown in Fig. 5. 70 The wheels 24 must be of the same diameter for all of the twisters to insure a uniform speed to all of said twisters, and as the next four of the latter are farther apart than the first five the cog-wheels 24 will not make engagement with each other. I therefore extend their shafts 23 and mount the larger cog-wheels 25^a thereon, thereby connecting said four shafts in a series, which is connected with the series comprised of the first five shafts by 75 the cog-wheels 26 and 27 on the extensions of the adjacent shafts of said series. In like manner the last five shafts are connected in series by cog-wheels 28, and that series is connected with the middle one by means of the 80 cog-wheels 29 and 30. One shaft of each of the three series has a sprocket-wheel 31, which is engaged by the link belt 21, whereby, in connection with the remaining aforesaid mechanism, all of the shafts 23, and through them 85 all of the twister-shafts, are uniformly rotated. The said twister-shafts are each provided with a central longitudinal hole, through which the horizontal wires 1 are threaded, and opposite said hole and diametrically opposite each 90 other are two holes longitudinal of said shaft, through which two of the cross-wires are threaded. One wire of each of these pairs is from a spool of the near or inner row of spools, and the other is from a spool of the far or 95 outer row of spools. The cross-wires will only be threaded through each alternate twister-shaft. Each twister-shaft will comprise five 100 separable parts, (see Figs. 9 and 10,) a middle cylindrical part upon which the wheel 25 is 105 mounted and having the integral middle cylinder-segments 32 on either side of the wheel 25, and the double pair of shorter integral cylinder-segments 33, having flat inner faces 110 which are parallel with the adjacent and also flat face of middle segment 32. Between said middle segments and each of the four outside shorter segments 33 are the removable cylinder-segments 34, which when placed as in Fig. 10 fill out the full contour of the twister-shaft. The above-described middle portion of the twister-shaft, which I call the "body" portion, is mounted in suitable transverse indents 115 in the top of a cross-bar 35, reaching across the frame A and also having suitable recesses to receive the wheels 25. The displacement of these parts is prevented by a cap-bar 36, also having suitable recesses to receive and hold the said body and wheels, as shown in Figs. 5 and 8. Mounted in suitable channels in the 120 top of the cross-bar 35, under the removable shaft-segments 34, are the longitudinally-reciprocating bars 37, with seats to receive the said segments, which seats also serve to give engagement between the bars and the seg- 125 130

ments, whereby when the joints of the twister-shaft are parallel with the direction of movement of the reciprocating bars and said bars are moved longitudinally the requisite distance the removable shaft-segments will be carried from its first shaft to the one next adjacent to it. Through these removable segments are the holes which carry the cross-wires. Deep grooves or notches 38 allow for the passage of the wires through the cog-wheels 25 and supporting-shaft, so that the cross-wires may be removed and introduced with perfect freedom laterally of said wheels. The bars 37 are in pairs on either side of wheels 25 and bearings for the said wheels. Each of the three previously-described series of twister-shafts has a separate pair of said longitudinally-reciprocating bars and each pair of bars are connected by link-bars 39, 40, and 41, respectively, with cross-bars 42, 43, and 44, respectively, at one end of the cross-bar 35, (see Figs. 6 and 7,) and the latter are connected by links or pitmen 45 with the lever 46. By a throw of the lever 46 all of the bars 37 are proportionately moved, so as to cause the cross-wire-carrying shaft-segments to change places with a set next to each one moved, and a reverse movement of said lever will bring them back to first position. The top removable twister-segments are moved in a like manner by means of the cap-plates 47, also in three sections for the three series of segments, which plates are connected by pitmen 48 with the lever 46 on the other side of its fulcrum, whereby the top twister-segments will be moved simultaneously with the movement of the lower one, but in an opposite direction, which is necessary in order to present the cross-wires in right relation to produce a diamond-mesh fence. The segments have the flanges 49, which enter corresponding grooves in their retaining seat and cap, whereby movement of said segments longitudinally of the twister-shaft is prevented. Said segments also have tubular guides 50 for the cross-wires, which are pivoted on trunnions at their inner end and are adjustable radially of the twisters at their outer ends, whereby the distances of the cross-wires from the horizontal wires may be regulated.

It will be recalled that wheel 10, with its mutilated side wheel, imparts an intermittent movement to the shaft 15 and that said intermittent movement is imparted through the described mechanism to the twister-shafts. These quiet intervals are for the purpose of allowing an exchange of twister-shaft segments.

Crossing the axis of revolution of the wheel 10 at right angles to shaft 15 is the shaft 51, which is supported by the frame A in suitable boxes 52. This shaft has the bevel-pinion 53, which is given a half-revolution, thereby imparting a like movement to the shaft twice during each revolution of wheel

10 by means of the teeth 54 54 on the side of wheel 10. The shaft 51 also carries the wing-plate 55, which slides along the flat face of track 56, extending between said cog groups 54 54. Depressions opposite the cog groups 70 allow the wing-plate to rotate while the pinion 53 is engaging said cogs 54. The shaft 51 has the end crank 57, which is connected by the link-bar 58 with the extension-arm 59 from the said lever 46. The shifting of the twister-segments is controlled from this lever 46.

I will next describe the carriers by means of which the wires are kept from entanglement before reaching the twisters. The spools 4, referred to in the early part of this specification as carrying the supply of cross-wires, are mounted between circular revolving heads 60, and the heads are connected by a half-cylindrical shell 61, which insures uniform rotation of the pair of heads for each spool. 80 These heads are separated sufficiently to prevent contact with each other, and they rest upon and are supported by an under row of heads 62, which are joined in pairs by means of shafts and situated so that each upper head 90 has a bearing equally upon two lower heads, and in consequence the number of lower heads is one greater than that of the upper row. The heads in both upper and lower rows have circumferential cogs, which mesh 95 with each other at the contact-points, whereby when rotary movement is given to one of the heads of a series all of those in the train connected with it will revolve, and by the arrangement above described the top row of 100 heads will all revolve in the same direction, while the bottom row will revolve all in the same direction, but oppositely to the direction of the top row. The row of heads next to the body A is driven by shafts 63 63, which 105 in turn are driven through bevel-gears 64 from the shaft 65, and the latter is driven by link-belt connection 66 from the revoluble shaft 9. The outer rows of heads are connected with the said inner row by means of 110 the respective shafts 67 67 and 68 68, whereby the heads in all four rows will be uniformly rotated.

69 represents rigid stationary plates, one for each row of heads, having circular openings through which the heads of the row or series to which the given plate belongs are inserted in the manner shown in Figs. 13, 14, 15, and 16. As shown in Fig. 16 and indicated by the inner dotted circles of Fig. 15, 120 the said heads have circumferential grooves 70, and into these grooves the plates enter by reason of the openings in said plates being less in diameter than the body of the head. The heads have transverse grooves 71, in which the fence-wires are laid. These grooves extend to about the bottoms of the circumferential grooves 70, and when the fence-wires are in the transverse grooves they will be carried around with the rotating heads and will 130

pass under or inside of the plates, the latter serving as guards to hold the wires in the transverse grooves except at certain predetermined points where it is desired to shift the wire from the groove of one disk into a similar groove in an adjacent disk or head. This shift is made coincident with the exchange of the cross-wires between the twist-ers, and as the twist-ers turn in alternate oppo-
 site directions a corresponding change in the direction of movement of carrying-heads is required. The horizontal wires 1 are first threaded through the grooves of the heads, one wire to each lower groove, when the heads are set or turned with wire-grooves on the lower sides. The wires 1, which run to the twist-ers having odd numbers, counting from the bottom of the fence, are threaded through the grooves in the bottom tier of heads, and the wires going to the even numbers of twist-ers are threaded through the grooves in the upper tier of heads. The cross-wires from the outer row of spools are threaded through the left sides of the upper row of heads of the inner row of spools. The wires from the inner row of spools are threaded through the adjacent spool-heads or heads next to the machine and are carried directly to the twister to which the horizontal wire from that spool is carried. All of the drums in both rows are rotated twice around. The drums in the upper rows by going in the same direction as the twist-ers to which their wires are connected twist each pair of cross-wires twice around the horizontal wire of that twister. The above movement of the carriers prevents a twist in the wires except on the inner side of the twist-ers. The twist-ers are halted after they have made two revolutions, and the shift in the cross-wires is made. Then the twist-ers are rotated two revolutions in a reverse direction. Simultaneously with the above shifts of the wires at the twist-ers the cross-wires are shifted laterally to a correspond-
 ing adjacent top carrier-head, and coincident with this shift of the cross-wires the horizontal wires change places from a lower drum to a higher one geared to it. The twist-ers and carriers are given two revolutions to twist the cross-wires around the set of horizontal wires of the new set of twist-ers. Then a reverse shift of wires is made back to the twist-ers and carriers from which they started, and the above-described operations are suc-
 cessively repeated throughout the weaving of the desired amount of fence. The twist-ers when in motion have a greater speed than the drums in order to make up the time lost by their pauses in crossing the wires. The hori-
 zontal wires 1 are shifted from a lower to upper head and back by the pointed end of the bent lever 62' in the outer set of carriers. There is one lever for each pair of heads, as shown in Fig. 16. The levers have the fixed pivots 63' and are pivotally secured at their

lower ends to a common shifting bar 64'. This bar 64' is shifted longitudinally by a crank 65' on a rock-shaft 66', which extends back under the machine-body A and has a crank arm which is connected by rod 67', Fig. 4, 70 with the crank 68' on shaft 69'. The latter shaft has a crank 70', which is connected by rod 71' with crank 72 on the shaft 73. The shaft 73 has the two bevel-pinions 74 and 75 placed diametrically opposite each other with 75 relation to the wheel 76. The wheel 76 turns with shaft 9, on which it is mounted, and has the group of bevel-teeth 77, which engage the bevel-wheels 74 and 75 during each revolution of wheel 76 and rotate said bevel-pinions one 80 complete revolution each time. Rotation of the latter, except when in contact with the teeth 77, is prevented by the wing-plates 78 at the inner ends of the bevel-wheels, which travel over the flat table 79, except when next 85 said teeth 77, where the depression 80 occurs, which permits the wings to rotate.

The handling of the wires for the inner tier of carriers is more difficult for the reason that the cross-wire from the outer spools must be 90 kept clear of entanglement, which requires that they be shifted back and forth between pairs of heads all in the top row after each double revolution. To make this transfer, I provide the small intermediate cog-wheels 81, 95 (see Figs. 13 and 15,) under which the wire 5 passes in going from right to left, Fig. 15, and over which the said cross-wire passes in going from left to right. The horizontal wires 1 are shifted from lower head to upper 100 and back by means of the pointed lever 82, similar to the lever 62, previously described, for the outer tier of heads. Levers 82 have in addition the pivotally-attached arms 83, which terminate with the curved guard 84 to 105 prevent the escape of the wire from the cogs of wheel 81 during transit. The arms each have the points 85, which cross the path of the wire in the upper wheel to its right when in the position shown by full lines in Fig. 15, and that position is the one into which it is forced by the spring 86, carried by the pointed end of lever 82. A stop consisting of a lug 87 from the stationary plate 69 arrests the arm in right position; but when the lever 82 is moved into the 110 position shown by the dotted lines in Fig. 15 a lug 88 on said lever engages the lug 89 on the hinge end of the arm 83 and raises the arm to the dotted position out of the path of the wire in the upper head. The shift of the wire 115 5 toward the right over the wheel 81 is com-pelled by the pointed lever 90, when it is thrown into the position shown by the dotted lines in Fig. 15. The lever 90 has the stationary pivot 91, and its upper end is pivotally secured to 120 the bar 92. The lower lever 82 is pivotally attached to a bar 93, which, as shown in Fig. 13, is part of a continuous frame, whereby both will move together. As the lower lever requires a longer throw than the upper one, 13

I provide the slot 94 in bar 92 to allow for difference in movement. The frame thus provided is longitudinally reciprocated by crank 95 on shaft 96. This shaft extends back under the machine and terminates with an arm 97, which is connected by a rod with the crank-arm 98 on shaft 99. The latter has the crank 100, which is connected by rod 101 with crank 102 on the shaft 51, which, as has been previously described, has an intermittent movement from wheel 10.

The wheels 102' are friction-wheels to help support the heads and make them run easy.

Located between the outer tier of horizontal spools and the vertical spools 2 are the tension-wheels 103 to keep the wires from reeling off of the spools 2 too rapidly.

Having thus fully described my invention, what I claim as new, and wish to secure by Letters Patent, is—

1. In a machine for weaving fence material having horizontal wires connected by cross diagonal wires, reels to hold the supply of wires for the horizontal strands, wire-twisters, through which the horizontal wires are passed, spools between the reels and the twisters to hold the wire-supply for the cross-wires, means after each twisting together of horizontal and cross wires for changing the cross-wires from one twister to the next and then back after the next twist, and revolving wire-carriers between the reels and the twisters to carry the wires for each twister in the same direction and with the same speed for each revolution that said twister is moving.

2. In a wire-fence-weaving machine, twisters having an intermittent movement, means for changing the direction of movement of the twisters after each pause, spools separate from the twisters for supplying wire to said twisters, means comprising rotating notched heads and shifting-plates for carrying said wires in the same direction that the twister connected with said carrying means is going, and means without changing said spools for changing the wires to a carrier going in the same direction as the twister at each reversal of the twister.

3. In a fence-weaving machine, wire-twisters, means for reversing the movement of said twisters after each twist, and wire-carriers between the wire-supply and the twisters in rows, of an upper and a lower series in each row, the upper series revolving in opposite direction from the lower one, and means for shifting the wires from one series to the other to correspond with the direction of movement of the twister supplied with wires from that carrier.

4. In a wire-fence machine, a plurality of rotating shafts each having a central wire and two other wires, the latter being diametrically opposite each other and off of the shaft-center, spools separate from and independent of said rotating shaft for supplying the outer wires, means without taking the spools for carrying

the outside wires to opposite adjacent twisting-shafts, means for twisting them around the central wires of said adjacent twisters and for returning them to the place of beginning and so on.

5. In a wire-fence-weaving machine, a plurality of rotating shafts each having a central wire and two other wires, the latter being diametrically opposite each other and off of the center of said shaft, spools separate from and independent of said rotating shaft for supplying the outer wires, means without taking the spools for carrying the outside wires to opposite adjacent twisting-shafts, means for twisting them around the central wires of said adjacent twisters and for returning them to the place of beginning and so on, and means between the supply reels or spools and the twisters for preventing the entanglement of the wires.

6. In a wire-fence-weaving machine, a plurality of rotating shafts each having a central non-removable portion and a double pair of laterally-removable shaft ends, a wire passing through the axis of each non-removable shaft portion, spools separate from and independent of said non-removable shaft and a pair of wires for said spools each passing through a pair of the removable shaft ends on diametrically opposite sides of the shaft-axis and means for moving the shaft ends back and forth laterally between pairs of twister-shafts without changing said spools, a shift being made after each twist.

7. In a fence-machine, a twister-shaft comprising five separable parts, viz: a middle cylindrical body portion having integral mid-cylinder segments from each end of said body, and four removable cylinder-segments to fill out the full cylinder contour of the twister-shaft.

8. In a fence-machine a twister-shaft comprising five separable parts, viz: a middle cylindrical body portion having integral mid-cylinder segments from each end of said body, and four removable cylinder-segments to fill out the full contour of the twister-shaft said middle body and integral extensions having a longitudinal wire-opening and said four removable segments being in connected pairs each pair comprising segments on the same side of the twister-shaft and each pair having wire-openings to receive one of the cross-wires, and means for shifting each pair of removable segments in opposite lateral directions from one twister-shaft to the next adjacent shaft and back, said lateral shifts being made after each wire-twisting operation.

9. In a fence-weaving machine a series of wire-twisters each having a central body portion through which one of the horizontal fence-wires is threaded, cylinder-segments on diametrically opposite sides of said body portions each having an opening to carry one of two cross-wires, a cog-wheel on each of said body

portions and revoluble shafts adjacent to said twisters having cog-wheels to engage the line-wheels of the said twisters.

10. In a fence-machine, shafts having an intermittent rotary movement, each of said shafts having a central longitudinal perforation through which one of the longitudinal fence-wires is threaded, and having two longitudinal perforations at points diametrically opposite each other and both off of said center through which two of the cross-wires of the fence are passed, the parts of the shaft carrying the cross-wires being separable from the remainder of the shaft, reciprocating bars above and below the twister-shaft centers having indents receiving the shaft ends and engaging the said separable end sections, a pivoted lever having a lateral arm, an intermittently-rotating shaft having a crank-arm connected with the lateral arm of said lever, and pitmen connecting the top reciprocating bars with said lever above the pivot thereof and other pitmen connecting the lower sliding bars with the said lever below its pivot.
25. 11. In a fence-weaving machine, a series of twister-shafts each having a middle cylindrical portion and removable segments on diametrically opposite sides of each end of each shaft, a cross-bar having top indents in which said shafts are seated, a top bar extending across said series having under side indents to receive the upper portions of said shafts and prevent their lateral movement, a cap over the top bar wider than said top bar having under side flanges with indents which engage the upper removable shaft-segments, bars below said flanges having upper indents to engage the lower segments, means for intermittently revolving the twister-shafts, and means during the pauses of said twister-shafts for longitudinally reciprocating said cap and lower bearing-bars whereby the removable shaft-segments will be moved laterally in opposite directions.

45. 12. In a fence-weaving machine, a frame, a continuously-rotating shaft mounted therein, said shaft having a wheel at either end, each of said wheels having a row of bevel-cogs less than a semicircle in length, and a table projecting from the side of the wheel having said cogs and extending between the ends of the row of cogs, and said wheels having depressions between the ends of said tables adjacent to the cogs, the two wheels being set so the cogs of one wheel will be diametrically opposite those of the other wheel, vertical shafts at either end of the above-named shaft each having a bevel-pinion to engage the teeth of the adjacent wheel on the said continuously-rotating shaft and said shafts having flat-sided wing-plates to contact with said tables and hold the vertical shafts stationary while the wings are in contact therewith, counter-shafts geared to said vertical shafts, twister-shafts, shafts parallel therewith and connected by suitable

gears and means for revolving the parallel shafts from said counter-shafts.

13. A shaft having a bevel-pinion, a flat-sided wing-plate extension from the pinion and a crank-arm, a continuously-rotating shaft at right angles to the first-mentioned shaft, a wheel mounted thereon having side teeth to engage the teeth of said pinion, the number of such side teeth being sufficient to impart a half-revolution to the first shaft and said wheel having a table to hold the wing-plate from turning, said table having a depression opposite the group of teeth to permit the wing-plate to rotate, twister-shafts having removable portions on two diametrically opposite sides to carry the cross-wires, caps to engage the top movable portions and shift them by the longitudinal movement of said caps, bars under the removable ends of said twister-shafts engaging said removable portions, a pivoted lever having an arm connected with the crank on the first-named shaft, and pitmen connecting the caps with said pivoted lever at points above the pivot, and pitmen connecting said under bars with the lever at points below the pivotal point of said lever.

14. In a fence-weaving machine, a number of wire-twisters equal to the number of longitudinal wires in the fence to be woven, carriers moving in opposite directions from every horizontal wire where a twist has just been made, to the next adjacent horizontal wire, spools of a number less by one than the number of longitudinal wires, each carrying a cross-wire and arranged in a double row, rotating heads in pairs, between each of which pairs one of said spools is mounted, said heads having peripheral cogs, an intermediate series of heads under those carrying the spools, said under heads having cogs and making driving connection between each pair of upper heads, and means for shifting the wires from one head to an adjacent one in harmony with the movements of the twister-shafts.

15. In a fence-weaving machine, a number of wire-twisters equal to the number of longitudinal wires in the fence to be woven, carriers moving in opposite directions from each horizontal wire around which a twist has just been made to the next adjacent horizontal wire, spools of a number less by one than the number of longitudinal wires, each carrying a cross-wire and arranged in a double row, rotating heads in pairs between each of which pairs one of said spools is mounted, said heads having peripheral cogs, an intermediate series of heads under those carrying the spools, said under heads having cogs and making driving connection between each pair of upper heads, and small cog-wheels between the upper series of heads of the inner row of carriers to carry the cross-wire from one top head to an adjacent one.

16. In a fence-weaving machine, a number

of wire-twisters equal to the number of longitudinal wires in the fence to be woven, carriers moving in opposite directions from each horizontal wire where a twist has just been made, to the next adjacent horizontal wire, spools of a number less by one than the number of longitudinal wires each carrying a cross-wire and arranged in a double row, rotating heads in pairs between each of which 5 a pair of heads one of said spools is mounted, said heads having peripheral cogs, an intermediate series of heads under those which carry the spools, said under heads having cogs and making driving connection between 10 the heads of each two adjacent upper spools, cross-wire-carrying pinions between the upper series of heads of the inner row of car-

riers, pointed levers each separately pivoted between its ends to fixed supports and at their lower ends to frames or bars reciprocating 20 longitudinally of the row of spools to which the frame relates and rocking shafts to reciprocate the respective frames and move the pointed levers across the paths of the wires to shift them from one carrying-head to another. 25

In witness whereof I have hereunto set my hand and seal at Indianapolis, Indiana, this 23d day of October, A. D. 1902.

GEORGE W. WHITTINGTON. [L. s.]
